BRACKET FOR AN ELECTRIC WATER HEATER

Henry C. Corson, Oakmont, and Lester D. Drugmand, Pittsburgh, Pa., assignors to Emerson Electric Company, St. Louis, Mo.

Filed Nov. 18, 1968, Ser. No. 14,513

Term of patent 14 years

Int. Cl. D8—03

U.S. Cl. D54—1

FIG. 1.

FIG. 2.

FIG. 3.

FIG. 4.

FIGURE 1 is a plan view of one face of a bracket, showing our new design,

FIGURE 2 is a plan view of the opposite face of the bracket,

FIGURE 3 is a side view of the bracket, and

FIGURE 4 is a sectional view corresponding to the line 4—4 of FIGURE 2.

We claim:

The ornamental design for a bracket for an electric water heater, substantially as shown.
